UNITED STATES PATENT OFFICE.

MAURICE J. CAFFREY, OF NEW YORK, N. Y.

BOOKHOLDER.

Application filed July 6, 1922. Serial No. 573,067.

To all whom it may concern:

Be it known that I, MAURICE J. CAFFREY, a citizen of the United States, and a resident of the city of New York, borough of Manhattan, in the county and State of New York, have invented a new and Improved Bookholder, of which the following is a full, clear, and exact description.

The present invention relates to new and useful improvements in book holders, and it pertains more particularly to a book holder adapted for attachment to an article of furniture, such, for instance, as a chair, bed, or the like.

15 It is one of the primary objects of the invention to provide a new and improved form of book holder which may be adjusted to various angles to meet the requirements of an article of this character.

20 It is a further object of the invention to provide a new and improved form of attaching means for securing the book holder in position on an article of furniture.

It is a further object of the invention to 25 provide a new and improved form of book holder which is adjustable in a horizontal and a vertical plane.

It is a further object of the invention to 30 provide a new and improved form of book holder in which means for maintaining the book in open position is employed.

With the above and other objects in view, reference is had to the accompanying drawings, in which—

35 Figure 1 is a top plan view of a new and improved book holder constructed in accordance with the present invention;

Fig. 2 is a longitudinal vertical sectional view thereof;

40 Fig. 3 is a detail horizontal sectional view taken on the line 3—3 of Fig. 2.

Referring more particularly to the drawings, the reference character 11 designates a substantially triangular bracket, and one 45 side of said triangular bracket is extended beyond its adjacent side as indicated by the reference character 12. The side which carries the extension 12 is secured to the adjacent side by means of a rivet or the like 13, and this side of the triangular shaped bracket is provided with a plurality of openings 14, the purpose of which will be hereinafter described. The extended portion 12 is flared as indicated at 16, and the edge of said flared portion is provided with a plurality of notches 15.

Carried by one of the sides of the triangular member 11 is a clamp consisting of two members 17, slidably mounted with respect to the plate 18, which plate is secured to the triangular bracket as at 19. Carried by the triangular bracket is a right- and left-hand screw-threaded member 20 mounted in a bearing member 21 and having screw-threaded engagement with the clamp members 17 as designated by the reference character 22. One end of this screw-threaded member is squared as at 23 in order that it may be engaged with a key to rotate the same to move the clamp members 17 toward and away from each other. The clamp members 17 are covered with rubber or the like 24, to prevent their scratching or marring the the article to which the device is attached.

The reference character 25 designates a 75 rod, one end of which is provided with a right-angular extension 26 adapted to engage in one of the openings 14 of the triangular member 11. The rod lies in one of the notches 15 of the flared portion 16. The opposite end of this rod is screw threaded for the reception of nuts 27, and clamped between said nuts 27 is a depending plate or bar 28. This plate or bar 28 has a plurality of openings 29, and said openings are adapted to receive the reduced screw-threaded end 30 of a rod 31, said screw-threaded end receiving a wing nut 32.

The opposite end of the rod 32 is flat as indicated by the reference character 33, and provided with an opening through which a screw, bolt, or the like, 34 passes, said screw, bolt or the like receiving a wing nut 35. This screw or bolt 34 is carried by a plate 36, and said plate 36 is provided with flanges 37 and 38.

Mounted on the plate and extending there-over are two arms 39, said arms being mounted on a bolt 40, which is surrounded by a spring 41 pressing upwardly against the arms 39, said arms being retained in place by means of a nut 42. By tightening or loosening this nut 42, the tension of the spring 41 may be varied at will.

The device operates in the following manner: The clamping members 17 are engaged with an article of furniture, as, for example, a chair, bed, or the like, and the member 20 is rotated so that the clamp members are caused to firmly grip the article of furniture to which the device is attached. After the device has been positioned, the book, maga-

zine, or the like, is placed upon the plate 36 and the arms 39 are engaged therewith to hold the book or magazine in open position. If the position of the plate 36 is not what is desired, the rod 25 may be engaged with either of the notches 15 to change the angular disposition of the plate 36 and said plate may be raised or lowered by engagement of the rod 31 with the openings 29 in the bar 28. If it is desired to extend the position of the plate 36, the right angular end 26 of the rod 25 is engaged with the outer opening 14 in the triangular-shaped bracket member.

From the foregoing it is apparent that the present invention provides a book holder in which various adjustments may be made in order that the proper positioning of the book relative to the reader may be had.

What I claim is:

20. A book support comprising in combina-

tion, an attaching means in the form of a clamp, a substantially triangular bracket carried by said clamp, said bracket having a plurality of openings in one of its walls and a projecting wall provided with a plurality of serrations, an arm adapted to be received in one of said serrations, said arm having a right-angular extension adapted to be received in one of the openings of the wall of the bracket, a vertically disposed arm dependent from the free end of said first-mentioned arm and provided with a plurality of openings, a rigid arm carried by said vertical arm and adapted to be secured in one of said openings, and a book-supporting member carried on the last-mentioned arm and adjustably secured thereto in a horizontal plane.

MAURICE J. CAFFREY.
